FLEXIBLE INSOLES PROVIDED WITH REMOVABLE FOREPART STIFFENING MEANS

Karl A. Stritter, Nahant, Mass., assignor to United Shoe Machinery Corporation, Flemington, N. J., a corporation of New Jersey

Application November 24, 1954, Serial No. 470,995

3 Claims. (Cl. 36—44)

This invention relates to insoles, more particularly to insoles for use in the manufacture of flexible, flat-lasted shoes.

An object of the invention is to provide an insole by the use of which a substantial yet very soft shoe of the flat-lasted type may be made and which may be held in place to retain the feather line of the shoe during operations on the shoe, the insole being released before the shoe is completed. To accomplish this object, a thin, flexible insole or body layer of a size and shape to cover at least the forepart of the bottom of a selected last is provided. To hold such an insole on the last bottom so as to permit an upper to be lasted over it without the insole being pushed in, rucked up or otherwise displaced thus destroying the feather line of the shoe, a stiffening plate and stiffening plate retaining means are provided.

The stiffening plate retaining means is a permanent insole member and is secured to the insole so as to form a rearwardly open pocket on the forepart thereof and may be made of a piece of sheet material such as fabric of horseshoe shape the outer boundary of which corresponds to the outer boundary of the forepart of the insole, these outer boundaries or peripheral portions being secured together close to their edges preferably by a fine seam. This form of stiffening plate retaining means provides a rand or strip about the forepart of the insole, to which rand the upper may be secured in lasted position by cement or by fastenings driven through the upper and rand. The rand also constitutes a lasting layer between the insole and upper.

In case the entire forepart of the upper is to be cement-lasted, the stiffening plate retaining means may be a piece of sheet material, such as coarse fabric, corresponding in size and shape to the forepart of the insole, the insole and the fabric piece being secured together about their curved peripheral portions and the rear end of the fabric piece being unsecured to the insole so that it forms a rearwardly open pocket. This pocket layer constitutes a lasting layer since the upper is secured to it. In either case, the stiffening plate is temporarily inserted into the pocket before the insole is tacked to the last bottom and may, after the tacks are removed, be withdrawn rearwardly from the pocket after it has served its purpose and may be used repeatedly. The stiffening plate is of a size and shape to snugly fit against the seam holding the stiffening plate retaining means to the body layer and is located, of course, between the stiffening plate retaining means and the body layer.

At the shank-and-heel portion of the insole a shank-and-heel piece of leather or fiber of substantial thickness is employed since flexibility in this part of a conventional shoe is not desirable. The shank-and-heel piece has a skived front end which is secured to the flexible forepart insole or, if the insole or body layer covers the last bottom, the shank-and-heel piece is cemented to the shank-and-heel portion of the insole or body layer. After the insole with the plate inserted is secured to the last bottom, an upper is assembled on the last, pulled over and

2

lasted to the insole, the heel end being lasted with tacks, the sides of the shank portion being held in lasted position, for example, by curved staples, and the forepart being lasted to the stiffening plate retaining means preferably by cement.

During the lasting of the forepart over the thin, flexible insole, the stiffening plate retains the outline of the insole and prevents any distortion or disturbance of the feather line.

- 10 The stiffening plate retaining means may be saturated with cement, in which case, after the upper is lasted to the stiffening plate retaining means and the stiffening plate withdrawn, the cement on the upper and on the stiffening plate retaining means may be activated by the application of heat and pressure to the shoe bottom, for example, by placing the shoe in a bottom ironing machine. By this treatment the lasting layer or stiffening plate retaining means is caused to adhere to the body layer of the insole. The cement bond between the upper and the lasting layer or stiffening plate retaining means is enhanced and the overlasted upper is smoothed out and wrinkles removed. After this treatment, which, however, may be omitted, the overlasted portion of the upper or lasting allowance may be roughened or cemented. The cavity between the edges of the upper may be filled with sheet cushioning material the thickness of which at its outer edge will be equal only to the thickness of the rand plus the thickness of the upper, if a rand is used, in case the stiffening plate retaining means covers the forepart of the insole, will be at its edge at least equal only to the thickness of the upper. A sole will now be cement-attached to the flattened lasting allowance of the upper, the result being a novel shoe construction in which a lasting layer is cemented to the body layer, the upper is cemented to the lasting layer, and the outsole is cement-attached to the upper. If a light appearing, close edge shoe is desired, a close edge sole may be attached to the shoe, preferably by cement. If the appearance of a welted shoe is desired, an extension sole 40 may be cement-attached and a stitchdown welt applied to the extension with its edge close against the upper and the welt sewed to the extension outsole.

In case the insole is to be used in making shoes in which the edge of the insole is exposed as in strap sandal, open heel or open toe work, the thin, flexible body layer may be extended beyond the stiffening plate retaining means at the forepart and, if desired, beyond the shank-and-heel piece, the extended portion being reduced in thickness by skiving or by a shoulder scarf and wrapped over upon the margin of the stiffening-plate retaining means where it is secured by a fine seam passing through the folded portion, the stiffening plate retaining means and the body layer of the insole. The extended portion at the heel and shank may be folded over upon the outer face of the shank-and-heel piece and secured thereto by cement.

Fig. 1 is a perspective view of the body layer of the insole with a shank-and-heel piece secured to its shank-and-heel portion;

Fig. 2 is a perspective view of a forepart body layer with a shank-and-heel piece sewed to the rear end portion of the forepart body layer;

Fig. 3 is a perspective view of one form of stiffening plate retaining means;

Fig. 4 is a perspective view of another form of stiffening plate retaining means;

Fig. 5 is a perspective view of the body layer of Fig. 1 with the stiffening plate retaining means of Fig. 3 sewed to the body layer;

Fig. 6 is a perspective view of the stiffening plate;

Fig. 7 is a cross-sectional view through the forepart of the shoe shown in Fig. 8;

Fig. 8 is a perspective view of a shoe lasted over the insole of Fig. 5 with the stiffening plate of Fig. 6 in place;

Fig. 9 is a sectional view taken on the line IX—IX of Fig. 8;

Fig. 10 is a perspective view of the insole of Fig. 2 with the stiffening plate retaining means of Fig. 4 secured thereto, the stiffening plate of Fig. 6 being in place between the body portion and the stiffening plate retaining means;

Fig. 11 is a fragmentary sectional view of the forepart of the shoe of Fig. 8 after a close edge sole has been cement-attached;

Fig. 12 is a view similar to Fig. 11 showing an extension edged outsole cement-attached to the shoe and a welt applied to the extension; and

Fig. 13 is a view similar to Fig. 10 showing an insole with a bound edge.

The insole of the present invention comprises an insole member having a thin, flexible forepart and a relatively thick and stiff shank-and-heel portion. This may be made by providing a body layer 10 (Fig. 1) to cover the bottom of a selected last. The layer 10 may be of sock lining material, upper leather or a grain or flesh spilt. To the shank-and-heel portion of the layer 10 may be attached, preferably by cement, a shank-and-heel piece 12 of thick, stiff material such as sole leather or fiber.

Sock lining stock may be saved by providing, in place of the layer 10, a forepart body layer 14 covering the forepart only of the last bottom and attaching thereto the skived front end of the shank-and-heel piece 12 (Fig. 2), for example, by a seam 16.

It is to be understood that either the insole member of Fig. 1 or that of Fig. 2 may be used in completing the insole in the manner to be described.

To complete the insole a stiffening plate 18 (Fig. 6) and stiffening plate retaining means 20 (Fig. 3) or 21 (Fig. 4), either of which is to be a permanent insole member, are provided. The plate 18 is shaped like the forepart of an insole but is slightly smaller and may be made of any thin, fairly stiff, sheet material such as steel or fiber. Since plastics, such as polyethylene, resist adhesion to cement, the plate may be made from a thin sheet of polyethylene. To facilitate handling the plate it is provided with a hand piece 22 projecting from its rear end.

The stiffening plate retaining means 20 is in the form of a rand or strip the outer edge of which corresponds to the outline of the forepart of the insole. It may be die-cut in this shape from a coarse fabric, such as buckram, and may be coated or saturated with cement. The rand 20 is placed upon either one of the insole members shown in Figs. 1 and 2 with its outer edge flush with the edge of the forepart of the insole or body layer and is attached thereto by a fine seam 24 located close to the edges of the parts, as shown in Fig. 5.

The stiffening plate retaining means 21 is made of the same material as the rand 20, is similarly cemented and is of the size and shape of the forepart of the insole or body layer. The stiffening plate retaining means 21 (Fig. 10) has its curved peripheral portion sewed to the curved peripheral portion of the forepart of the body layer of the insole, the layer 21 forming a complete layer on the forepart of the insole and in each case the rand 20 or the layer 21 forms a rearwardly open pocket into which the stiffening plate 18 may be slipped, as shown in Figs. 7, 8, and 10. The plate 18, in either case, fits against the seam 24 and serves to render the limp part of the insole sufficiently stiff to permit the lasting of an upper over it without its being wrinkled or rucked up.

Either insole thus prepared is secured to the bottom of a last L (Fig. 8) by tacks 26 driven through the plate 18 or through the stiffening plate retaining means 21 and the plate 18 to hold the insole in place on the last bottom, the plate serving to maintain the feather line of the shoe during lasting. An upper 30 is assembled on the last and

the shoe is pulled over and lasted by usual procedures as to the shank and heel, the heel-seat, for example, being lasted with tacks 34 and the sides of the shank by curved staples 36 (Figs. 8 and 9). The inner surface of the lasting allowance 32 at the forepart may be provided with cement and the cement on the stiffening plate retaining means 20 or 21 rendered active if necessary. The upper 30 (Fig. 8) is then tensioned and its lasting allowance 32 laid over the stiffening plate retaining means 20 or 21 in finally lasted position to be held by the cement. At the toe, of course, a bed lasting machine or an automatic toe lasting machine may be used. When the stiffening plate retaining means is in the form of the rand 20, the sides of the forepart may, if desired, be secured in lasted position by inserting fastenings such as staples through the upper and rand and clinching them on the under side of the rand. During lasting, any pressure tending to displace or ruck up the insole at the forepart is opposed by the plate 18, which is confined by the seam 24 and by the stiffening plate retaining means to the insole which is held by the tacks 26 to the last. Thus, the outline of the insole or the feather line of the shoe is unchanged. After the shoe is lasted the tacks 26 are pulled and the stiffening plate 18 is withdrawn by seizing the hand piece 22 and pulling the plate rearwardly of the shoe for use over and over. The overlasted margin of the upper is roughened and cemented and any excess of upper extending beyond the rand 20 may be trimmed off.

In order to secure the stiffening plate retaining means 30 of either form and the lasting allowance in flat condition against the body layer 10, the shoe may be subjected to a bottom ironing operation in which the shoe bottom is subjected to heat and pressure. This operation on the shoe may be performed by a machine of the type disclosed in United States Letters Patent No. 2,175,474, granted October 10, 1939, upon an application of Axel A. Lawson. The heat and pressure thus applied cause the cement on the stiffening plate retaining means to adhere to the insole and that on the upper to adhere more firmly to the stiffening plate retaining means. The lasting allowance 32 of the upper will also be smoothed out and wrinkles eliminated. A shank stiffener may now be applied to the shank portion of the shoe and a cushion filler 38 applied to the forepart.

If a shoe of close-edge appearance is desired, a close-edge sole 40 may be cement-attached, as indicated in Fig. 11. If a shoe resembling a welt shoe in appearance is desired, an extension sole 42, as shown in Fig. 12, may be cement-attached and a stitchdown welt 44 crowded against the shoe upper and secured by a seam 46 to the outsole. A heel will be attached and the shoe finished in the usual manner.

In case shoes having uppers which do not conceal the entire edge of the insole are to be made, the subject insole may have a bound or covered edge (Fig. 13). In this case the insole body member 10 may be sufficiently enlarged to permit skiving or shoulder scarfing its peripheral portion so that the scarfed margin may be folded over the stiffening plate retaining means and secured thereto at the forepart by the peripheral seam 24 holding the stiffening plate retaining means and the insole member together. At the shank and heel the insole may be folded over the shank-and-heel piece and cemented to its outer surface. The insole edge may be thus bound irrespective of which form of stiffening plate retaining means is employed.

Having thus described my invention, what I claim as new and desire to secure by Letters Patent of the United States is:

1. An insole for shoes comprising a thin flexible body layer, and stiffening plate retaining means having the outline of the forepart of an insole, the body layer being extended beyond the stiffening plate retaining means and being reduced in thickness on its extended marginal portion, said marginal portion being wrapped over the edge

of the stiffening plate retaining means and secured thereto by a seam passing through the reduced portion, the stiffening plate retaining means and the body layer of the insole.

2. An insole for shoes comprising a thin, flexible body layer, and stiffening plate retaining means having the outline of the forepart of an insole, the body layer being extended beyond the stiffening plate retaining means, the marginal portion of said body layer being wrapped over the edge of the stiffening plate retaining means and secured thereto by a seam passing through the marginal portion, the stiffening plate retaining means, and the body layer of the insole.

3. An insole for shoes comprising a thin, flexible body layer, a removable stiffening plate of a shape corresponding to, but somewhat smaller than, the forepart portion of said body layer and adapted to reinforce said forepart portion during the lasting of a shoe upper, and stiffening plate retaining means having the outline of the forepart of the insole, the body layer being extended beyond the stiffening plate retaining means, the marginal portion of said body layer being wrapped over the edge of the stiffening plate retaining means and secured thereto by a seam passing through the marginal portion, the stiffening plate retaining means, and the body layer of the insole.
